UNITED STATES PATENT OFFICE.

PAUL FLEMMING COX, OF JACKSON, MICHIGAN, ASSIGNOR TO JACKSON PRINTING PRESS COMPANY, A CORPORATION OF MICHIGAN.

WEB-PRINTING PRESS.

No. 884,901.

Specification of Letters Patent. Patented April 14, 1908.

Application filed February 3, 1908. Serial No. 414,008.

To all whom it may concern:

Be it known that I, PAUL FLEMMING COX, of Jackson, in the county of Jackson and State of Michigan, have invented certain new and useful Improvements in Web-Printing Presses; and I hereby declare that the following is a full, clear, and exact description thereof, reference being had to the accompanying drawings, which form part of this specification.

This invention is an improvement in printing presses and has particular reference to the means for controlling the rotation of the cylinders relatively to the movement of the bed, and is particularly designed for use in presses such as shown in Patent No. 847,912, granted to me on the 19th day of March, 1907. In such press the cylinders are rotated continuously in one direction while the bed is reciprocated back and forth thereunder. The cylinders take impressions from the type on one stroke of the bed, and the impression is thrown off during the return stroke of the bed.

In the present invention the periphery of the cylinders is moved in unison with the type form by means of segmental gears on the cylinders engaging racks on the bed, and when the impression is thrown off the cylinders are caused to continue to rotate, in a forward direction, during the return movement of the bed by means of a pair of toothed segments which operate a lay-shaft and gearing between said shaft and cylinders. The segments are in mesh when the bed rack and cylinders are out of mesh and vice versa.

The invention will be fully understood from the accompanying drawings and the following explanation, said drawings only illustrating such parts of the press as are necessary to impart a clear understanding of the invention.

In said drawings—Figure 1 is a side elevation of part of a bed-and-cylinder web-printing press, showing means for reciprocating the bed and for rotating the cylinders continuously in one direction. Fig. 2 is a longitudinal section through Fig. 1. Figs. 3, 4, 5, 6 and 7, are diagrammatic views illustrating the various positions of the parts assumed during one reciprocation of the bed.

As shown in the drawings, the type bed B can be reciprocated by pitman C, connected to hangers B', on the bed and to crank pins j on crank gears J, mounted on the main shaft

J', and driven by a pinion K, on a shaft k, which may be driven in any suitable manner.

Above and coacting with bed B, are two impression cylinders A, A, and to each cylinder is secured a cylinder gear D, the teeth of which extend only part way around its periphery, the untoothed spaces of its periphery being indicated by E, Figs. 1 and 2.

Secured to bed B, are two racks F, F, adapted to engage and co-act with the respective cylinder gears D. These racks F, F, are shorter than the travel of the bed, but are somewhat longer than the type forms, indicated at G, Fig. 2, on the bed. The racks are so located that the gears D will be securely in mesh therewith before the cylinders A contact with the forms G. By this means the cylinders A, A, are rotated in unison with the type forms during impression. After impression and when the gears D go out of mesh with racks F, the rotation of the cylinders is continued in the same direction by the following means: Secured to the shaft J', is a segmental gear or segment H, meshing with a segmental gear or segment I, secured to a parallel shaft I'. On shaft I' is a bevel gear I² which meshes with a bevel gear L' on a lay-shaft L, which extends alongside of the bed, and at the ends of the cylinders A, and is journaled in suitable bearings as shown. The shaft L carries bevel gears L², meshing with bevel gears A² on the shafts of the cylinders A, as shown in Fig. 1. When the segmental gears, H, I, are out of mesh, the lay-shaft will be driven from the cylinders A, A; but when the cylinder gears D, and bed racks F, are out of mesh, the shaft L will be driven by the segments H, I, in proper time and manner to continue the forward rotation of the cylinders A, A.

The segments H and I are so proportioned that they will drive the cylinders A, A, through the lay-shaft L, and gears, at a peripheral speed exactly equal to that of the bed movement when the crank-pin j is at the point indicated at c, in Fig. 3, (or at the point c' in Fig. 5). At this time, when the parts are in the position indicated in Fig. 3, the cylinder gears D, and bed racks F, are just coming into mesh, and at this moment the cylinders pass from the control of the segments H, I, into the control of the cylinder gears D, and bed racks F.

When the parts are in position indicated in Fig. 5, the bed is just losing control of the

cylinders (racks F just going out of mesh with gears D) and the segments H, I, are just taking control of the cylinders through shaft L. The parts are so arranged that the cylinders are driven part of the time and during impressions by the bed, and thereafter their rotation is completed by the action of lay-shaft L driven by the segments H, I.

The cylinders A revolve in one direction continuously and the gearing is so proportioned that the cylinders make one revolution to each reciprocation of the type bed, and each revolution of the crank-shaft J'.

The diagrams, Figs. 3, 4, 5, 6 and 7, show the positions assumed by the respective cylinder driving devices during one rotation of the cylinders, or one stroke of the bed. In said diagrams, the lines *h*, *i*, represent the teeth of the segments H, I; the teeth of the gears D are represented by lines *d*; and the teeth of racks F on bed B are represented by lines *f*.

As illustrated in Figs. 1, 2 and 3, the bed is traveled a short distance on its forward stroke. The teeth *h*, *i*, of segments H, I, are just about to disengage and the teeth *f*, *d*, of racks F and gears D, have just engaged.

Fig. 4 shows the bed in the middle of its forward stroke, the segments H, I, being now disengaged, and the cylinders are rotated by the engagement of the teeth *f*, *d*, of bed racks F, and cylinder gears D.

Fig. 5 shows the bed near the completion of its forward stroke; the teeth *h*, *i*, of segments H, I, are now just engaging and the teeth *f*, *d*, of racks F and gears D are just ready to disengage.

Fig. 6 shows the bed at the end of its forward and the beginning of its return stroke. The teeth *h*, *i* of segments H, I, have again come into mesh and will now drive the cylinders A, A, through the lay-shaft L and gearing. The teeth *f*, *d*, of racks F and gears D are wholly disengaged, while the impression is thrown off.

Fig. 7 shows the bed in the middle of its return stroke, the teeth *h*, *i*, of segments H, I, being still in engagement; and the teeth *d*, *f*, of gears D, and racks F, are out of engagement; the impression being still thrown off.

By the mechanism above described it will be seen that the cylinders are driven continuously in one direction; they are driven during impression by the bed racks and cylinder gears, and that when the impression is thrown off their rotation is continued by reason of their gearing to the lay-shaft which is then positively driven by the segments H and I. During impression the segment I is driven from the cylinders, through the lay-shaft and gearing, in proper time to mesh with segment H, just before the bed racks go out of mesh with the cylinder gears; and while the impression is thrown off the cylinders are driven from the lay-shaft so that the

cylinder gears D will come into proper position to mesh with the bed racks F, before the cylinders again come into printing contact. By this means the web can be continuously fed through the press by the cylinders, substantially as described in my Patent No. 880,282, dated February 25, 1908, without the use of looping mechanism.

The course of the web through the press and the guides for the press are clearly indicated in Figs. 1 and 2, and are similar to that shown in my said patent, and therefore need no detailed explanation herein.

Having thus described my invention what I claim and desire to secure by Letters Patent is:

1. In combination, a reciprocating type bed, a cylinder co-acting therewith, a segmental cylinder gear, a bed rack engaging therewith for driving the cylinder in one direction; a lay-shaft, gearing between said lay-shaft and the cylinder, and segmental gears for actuating the lay-shaft when the bed rack and cylinder gear are out of mesh.

2. In a printing press, the combination of a reciprocating type bed, a cylinder co-acting therewith, a bed rack and a segmental cylinder gear engaging therewith for rotating the cylinder during impression, a lay-shaft and gearing between said shaft and said cylinder, and means for driving the lay-shaft to cause the cylinder to complete its rotation when the impression is thrown off.

3. In a printing press, the combination of a reciprocating type bed, an impression cylinder co-acting therewith, a crank shaft and pitman for operating the bed, a segmental gear on the cylinder, a co-acting bed rack on the bed, for rotating the cylinder during impression; segmental gears driven by the crank shaft, and gearing operated by said segmental gears for completing the rotation of the cylinder after impression.

4. In a printing press, the combination of a reciprocating type bed, an impression cylinder co-acting therewith, a segmental gear on the cylinder, a bed rack on the bed adapted to engage said segmental gear and rotate the cylinder during impression, a crank shaft and pitman for reciprocating the type bed, a lay-shaft geared to the cylinder, and segmental gearing for operating said lay-shaft to continue the forward rotation of the cylinders while the cylinder gear and bed rack are out of mesh.

5. In combination, a reciprocating type bed, a cylinder co-acting therewith, a bed rack, and a segmental cylinder gear for driving the cylinder during impression, a lay-shaft, bevel gearing between said cylinder and said shaft, and segmental gears for driving said lay-shaft when the bed-rack and cylinder-gear are out of mesh.

6. In combination, a reciprocating type bed, a cylinder co-acting therewith and

adapted to rotate continuously in one direction, a rack on the bed, a segmental gear on the cylinder engaging said rack for rotating the cylinder during impression, a crank shaft 5 and connections for reciprocating the type bed, a lay-shaft, and gearing between said shaft and cylinder, a segmental gear on the crank-shaft and gearing between said segment and the lay-shaft for actuating the 10 latter so as to cause the cylinders to continue to rotate in the same direction, while the bed-rack and cylinder-gear are out of mesh.

7. In a printing press, the combination of 15 a reciprocating type bed, a pair of cylinders simultaneously co-acting therewith, segmental gears on the cylinders, and racks on the bed adapted to engage the cylinder gears and rotate the cylinders during impression; with a segmental gear, means for rotating 20 said gear once for each reciprocation of the bed, and gearing between said segmental gear and the cylinder shaft for completing the rotation of the cylinders after impression.

8. In a printing press, the combination of 25 a reciprocating type bed, a pair of cylinders co-acting therewith, bed racks, segmental gears on the cylinders engaging said racks to rotate the cylinders during impression; a lay-shaft, gearing between said shaft and 30 each cylinder for continuing the rotation of the cylinders while the impression is thrown off, and means for driving the lay-shaft when the bed-racks and cylinder-gears are out of mesh.

35 9. In a printing press, the combination of

a reciprocating type bed, a pair of impression cylinders co-acting therewith, a segmental gear on each cylinder, bed-racks on the bed adapted to engage said segmental gears and rotate the cylinders during impression; 40 a crank-shaft and pitman for reciprocating the type bed; a lay-shaft geared to the cylinders, and gearing for operating said lay-shaft from said crank-shaft to continue the forward rotation of the cylinders 45 while the impression is thrown off, and the cylinder gears and bed racks are out of mesh.

10. In combination, a reciprocating type bed, a pair of cylinders co-acting therewith and adapted to rotate continuously in one 50 direction, racks on the bed, segmental gears on the cylinders engaging said racks and rotating the cylinders during impression; a crank-shaft and connections for reciprocating the type bed, a lay-shaft and gearing between said shaft and cylinders, a segmental gear on the crank shaft, and gearing between 55 said segmental gear and the lay-shaft for actuating the latter so as to cause the cylinders to continue to rotate in the same 60 direction when the bed racks and cylinder gears are out of mesh.

In testimony that I claim the foregoing as my own, I affix my signature in presence of two witnesses.

PAUL FLEMMING COX.
